[21] Appl. No.: 678,766

[57] CLAIM

The ornamental design for a cover for a tissue dispenser, as shown and described.

[22] Filed: Apr. 21, 1976

DESCRIPTION

[51] Int. Cl. ..... D6—13

FIG. 1 is a top plan view of a cover for a tissue dispenser showing my new design;
FIG. 2 is a right side elevational view, the left side being substantially a mirror image thereof;
FIG. 3 is a front elevational view;
FIG. 4 is a rear elevational view; and
FIG. 5 is a bottom plan view.
